UNITED STATES PATENT OFFICE.

CHRISTIAN WILLIAM MEINECKE, OF JERSEY CITY, NEW JERSEY, ASSIGNOR
TO MEINECKE & CO., OF NEW YORK, N. Y., A CORPORATION OF NEW JERSEY.

DESIGN FOR A CUSHION.

SPECIFICATION forming part of Design No. 35,470, dated December 24, 1901.

Application filed October 8, 1901. Serial No. 78,002. Term of patent 14 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for a Cushion, of which the following is a specification.

My invention relates to a new and original design for cushions, and is illustrated in the accompanying drawings, in which—

The leading feature of my invention resides in a cushion the body of which is of oval or oblong configuration and is formed with a substantially central opening which is not only oval or oblong in contour, but is disposed at right angles with, or has its major axis at a right angle to the major axis of the cushion-body, whereby a strikingly-distinguished appearance is imparted to the cushion.

In the said drawings the letter a indicates the cushion-body, which is oval or oblong in configuration, and b indicates the substantially central opening thereof, which, as shown, is not only oval or oblong in contour, but is disposed at right angles with, or has its major axis at a right angle to the major axis of the cushion.

My design presents a cushion having a novel, pleasing, and distinguished appearance.

What I claim as new, and desire to secure by Letters Patent, is—

The design for a cushion, substantially as herein shown and described.

In testimony whereof I have hereunto set my hand in the presence of two subscribing witnesses.

CHRISTIAN WILLIAM MEINECKE.
